UNITED STATES PATENT OFFICE.

JAMES G. WILSON, OF HOUSTON, TEXAS.

WIRES-TIGHTENER.

1,307,650.

Specification of Letters Patent. Patented June 24, 1919.

Application filed August 18, 1917. Serial No. 187,006.

To all whom it may concern:

Be it known that I, JAMES G. WILSON, a citizen of the United States, residing at Houston, in the county of Harris and State 5 of Texas, have invented certain new and useful Improvements in Wire-Tighteners, of which the following is a specification.

This invention relates to new and useful improvements in a wire tightener.

10 The object of the invention is to provide a device of the character described which is adapted to be used for the purpose of tightening the strands of wire of a wire fence so as to take up the sag between the 15 posts. The strands of wire fences after a time become loose and sag and it becomes necessary to tighten the strands and this device has been designed for the purpose of taking up said sag.

20 Another object of the invention resides in the provision of a wire tightener which will be cheaply and easily constructed and which may be easily applied for the purpose for which it is intended.

25 With the above and other objects in view, the invention has particular relation to certain novel features of construction, operation and arrangement of parts, an example of which is given in this specification and 30 illustrated in the accompanying drawings, wherein:

Figure 1 is a plan view of the device.

Fig. 2 is a side elevation thereof.

Fig. 3 is a front view.

35 Fig. 4 is an enlarged side view of the frame, and

Fig. 5 is an enlarged rear view of said frame.

Referring now more particularly to the 40 drawings, wherein like numerals of reference designate similar parts in each of the figures, the numeral 1 refers to a fence post which supports the wires 2, said wires being secured to the post by means of the staples 3 in the ordinary and well known manner. The tightener includes the frame 4, the handle 5, and the wire engaging links 6, 6. The frame is composed of a comparatively wide U-shaped member 7 having the legs 8, 8, spaced apart, said legs being connected by means of the arcuate bridge 9 which is integral therewith and spaced from the back

of the frame. The back part of the frame has an oblong slot 10 through which the handle 5 is inserted and the inner end of 55 said handle is provided with a transverse pin 11 which is inserted through said end, said pin being provided to prevent the detachment of the handle from the frame. The links 6, 6 are pivoted to the handle and 60 said links are spaced apart so as to embrace the fence post when in use, the under edges of said links being provided with ratchet teeth as 12 to engage with the wire on each side of the post. 65

In tightening the wire, the frame is placed against the post opposite the wire to be tightened, as shown in Figs. 1, 2 and 3 and the free end of the handle elevated, teeth 12 engaging over the wire on each 70 side of the post, and the sharp spikes 13, 13, projecting from the corresponding legs 8 engaging with the post to prevent the slippage of the frame. The free end of the handle is then forced downwardly into the 75 position shown in dotted lines in Fig. 2, the inner end of the handle bearing against the bridge 9. This will exert a backward pull through the links 6 and will draw the wire on each side of the post around against the 80 sides of the post as shown in dotted lines in Fig. 1. A tie wire 14 is then secured to the wire 2 up close to one side of the post and is drawn around said post and its other end secured to the wire to be tightened 85 at the other side of said post, thus securing the wire to be tightened in position and taking up the slack in it between the posts on each side. As the work progresses, the tightener is moved from post to post and 90 while being moved, the links 6 rest upon the lateral arms 15, 15 projecting out from each side of the frame.

What I claim is:

A wire tightener, including a U-shaped 95 frame member, having an oblong slot therethrough, an arcuate bridge connecting legs of the frame, said bridge being spaced from the back of the frame and forming an opening therethrough, a handle, one end of 100 which is inserted through said slot, a transverse pin extending through the inner end of said handle and opening, to prevent its detachment from the frame, said bridge

forming a bearing for the inner end of the handle, a pair of links pivoted at one end to the handle in the rear of said frame member, said links operating on opposite 5 sides of the frame, and having their other ends free, and being serrated to form wire

engaging teeth, a laterally projecting arm carried by each side of the frame, and provided to form supports for said links.

In testimony whereof I have signed my 10 name to this specification.

JAMES G. WILSON.
